Primary Examiner — Michelle E. Wilson*Assistant Examiner* — Jessie A Kwasney*(74) Attorney, Agent, or Firm* — Barley Snyder**CLAIM**

The ornamental design for a live single catch mouse trap as shown.

DESCRIPTION

FIG. 1 is a top, front and right perspective view of a live single catch mouse trap, showing the new design;

FIG. 2 is top, rear and right perspective view thereof;

FIG. 3 is a bottom, front and right perspective view thereof;

FIG. 4 is a bottom, rear and right perspective view thereof;

FIG. 5 is a rear elevation view thereof;

FIG. 6 is a right-side elevation view thereof;

FIG. 7 is a top plan view thereof;

FIG. 8 is a bottom plan view thereof; and,

FIG. 9 is a front elevation view thereof.

The broken line showing of live single catch mouse trap is included for the purpose of illustrating portions of the "article" and forms no part of the claimed design.
